CLAIM

The ornamental design for a hitch receiver cover embellished with an illuminated jack-o-lantern, as shown and described.

DESCRIPTION

FIG. 1 is a front, upper view of a hitch receiver cover embellished with an illuminated jack-o-lantern showing my new design;

FIG. 2 is a left view thereof;

FIG. 3 is a rear, upper view thereof;

FIG. 4 is a rear, upper right view thereof. The cable that connects the illuminated jack-o-lantern to a vehicle brake switch is shown in broken lines for illustration purposes only and forms no part of the claimed design;

FIG. 5 is a top view thereof; and,

FIG. 6 is a bottom, right view thereof.
